UNITED STATES PATENT OFFICE.

JEAN LACAPE, OF PARIS, FRANCE, ASSIGNOR TO J. LACAPE & CO., OF SAME PLACE.

MECHANICAL MUSICAL INSTRUMENT.

SPECIFICATION forming part of Letters Patent No. 272,269, dated February 13, 1883.

Application filed October 4, 1882. (No model.)

To all whom it may concern:

Be it known that I, JEAN LACAPE, a citizen of the French Republic, residing in Paris, in said Republic, have invented certain new and useful Improvements in Mechanical Musical Instruments, of which the following is a specification, reference being had to the accompanying drawings.

This invention is applicable to all mechanical musical instruments in which the execution of musical pieces is obtained by notation on cylinders, the rotation of which is effected by hand, foot, or other power.

The invention consists in novel means of effecting and controlling the longitudinal movements of the cylinder for the purpose of changing the tunes, as hereinafter described and claimed.

In the accompanying drawings, Figure 1 is a transverse vertical section of an upright piano with my invention applied. Fig. 2 is a front elevation of the cylinder and its driving mechanism. Fig. 3 is a side elevation, partly in section, of the driving mechanism on a larger scale than Figs. 1 and 2. Fig. 4 is a front view of the cylinder and its driving apparatus, partly in section, corresponding in scale with Fig. 2. Fig. 5 is a side view of the mechanism for operating the cylinder to change the air. Fig. 5* is a front view of one end of the cylinder and of the changing mechanism, partly in section. Figs. 6 and 7 are side views of the spring-key, through which the cylinder acts on the striking-action.

Fig. 1, is the treadle, situated at one side of and in or nearly in the same horizontal plane with the pedals existing in ordinary piano-fortes. It is articulated at *b* to the lower part of the case or frame *c* of the instrument, and is connected by a short connecting-rod, *d*, with a lever, *e*, one end of which is attached to a fixed fulcrum-pivot, *f*, (see Fig. 2,) and the other end of which is connected by a rod, *g*, with a crank-wrist on the fly-wheel. The fly-wheel *h* is loose upon the extremity of a horizontal shaft, *i*, but it is connected with the said shaft by a spring-pawl, *i'*, and ratchet-tooth, *i''*, when the treadle is put in motion in the proper direction. The shaft *i* is free to turn in bearings *j*, Fig. 1, fixed upon the

framing *k* of the instrument, and it is furnished with an endless screw, *i**, which gears with a worm-wheel, *l*, which is fitted to turn loosely, but not to move longitudinally, upon an axle, *m*, which is firmly bolted to the framing *k*. 55 This axle is prolonged to form a pivot for one end of the rotary music-cylinder *p*, which is boxed centrally for its reception, as shown in Fig. 4. The said wheel *l* has attached to its face which is next the cylinder a finger or carrier, *n*, which enters a hole in the cylinder for the purpose of causing the latter to be driven by and rotate with the said worm-wheel. On the same side of the said wheel is the head of a regulating-screw, which serves to arrest 60 the cylinder in its longitudinal motion toward the said wheel. On the other face of the said wheel *l* there is a slight projection, *l'*, which during every revolution of the said wheel lifts a lever, *l''*, (see Figs. 1, 3, and 4,) intended to 65 lift an indicating-needle, *l'''*, visible on the keyboard of the piano at each change of the air.

The music-cylinder *p*, having upon its circumference the points of notation of the airs, is mounted in a special manner. At one end 75 the cylinder rests, as has been already described, on the pivot formed by the fixed shaft *m*, and at the other end it is furnished with a central gudgeon, *q*, which constitutes a journal working in a bearing in a metallic support, *r*, 80 shown in Fig. 2, secured to the framing of the piano. The cylinder, besides its movement which is transmitted to it by the worm-wheel *l* and finger or carrier *n*, has a longitudinal movement, which permits it to automatically 85 bring the points on its circumference corresponding with each air in proper relation with the fingers of the special spring-key. The exact position of the cylinder during its rotation is determined by a sort of knife-edged 90 slide, *C*, which will be hereinafter described. The gudgeon *q* of the cylinder has in it circular grooves *s*, equal in number to the airs noted on the cylinder, and the width of the spaces between these grooves is equal to the 95 thickness of the notation-points. Moreover, the extremity of the gudgeon is screw-threaded, and carries upon it a nut, *t*, furnished with a projection or pin on its circumference, which at each change of air strikes against a roller, 100

t', (see Fig. 4,) which is arranged on a pin fixed in the support *r*, the purpose of this contact being, first, to present one of the grooves *s* in proper relation to the knife-edged slide *C*, and, 5 second, to present the points of notation of an air on the cylinder in proper relation to the fingers upon which they operate to play mechanically. During a revolution of the cylinder the projection on the nut *t* strikes against 10 a pin, *u*, fixed in the support *r*, in such manner as to cause the said nut to turn back upon the threaded part of the gudgeon *q* a distance equal to the interval comprised between two of the grooves *s* in the said gudgeon. This 15 turning back of the nut permits, when the changing of the air takes place, the longitudinal displacement of the cylinder, which is effected by means of a spring, *v*, (see Figs. 2 and 4,) which is attached to the support *r*, and 20 presses constantly against the adjacent end of the cylinder. Each air lasts during one revolution of the cylinder, and when it is desired to play the same air several times in succession it is only necessary to allow the cylinder to make as many revolutions in succession as 25 may be desired without longitudinal movement. In such case the nut *t* does not again encounter the projection *u*, but remains fixed upon its screw-thread at a distance from the 30 roller *t'* equal to the pitch of the thread or of the thickness of one of the grooves *s* and an intervening space; but when it is desired to change the air, and for that purpose the button *x* is pulled to withdraw the slide *C* from 35 the groove *s* in the gudgeon *q*, the spring *v* pushes the cylinder to the proper position, where it is stopped by the nut *t* coming in contact with the roller *t'*, the distance of the movement being always regulated by the pitch of 40 the screw-thread, and the position being always regulated by the nut *t* coming against the roller *t'*.

The mechanism for changing the air is operated by a button, *x*, terminating a rod, *y*, 45 passing through the forward part, 2, of the case of the piano below the key-board. The rod *y* is connected with a lever, *A*, fulcrumed at *B*, (see Figs. 5, 6, 7,) upon the support *r*. (See Fig. 5.) The lower part of this lever is 50 forked to receive a stud on the slide *C* for the purpose of moving the latter. This slide *C*, which is furnished with a sort of knife or knife-edge, *D*, intended, when the operation of the button *x* to start or change the air 55 takes place, to enter one of the grooves *s* of the gudgeon *q* in such manner as to render the cylinder immovable lengthwise, and also to regulate exactly the position of the pins or points on its circumference in relation to the 60 fingers *L* of the spring-key, which will be hereinafter described. The action of the knife does not interfere with the rotary motion of the cylinder. At the same time, as the knife 65 *D* takes position in one of the grooves of the gudgeon of the cylinder, the spring-key puts itself in range with the points of the cylinder. To this effect the upper part of the lever *A*

is furnished with a long nose, *E*, intended to hook onto the spring-key and to hold it constantly in contact with the cylinder. (See Fig. 6.) When, on the contrary, the key is not in operation, the roller *F* on an elbow-lever, *G*, operated by the lever *A*, supports the key. (See Fig. 7.) The key extends the whole length of the cylinder, and carries as 75 many fingers *L* as there are circumferential rows or ranks of points on the cylinder. It is furnished at its extremities with journals *K*, fitted to bearings in slides *H* and *I*, (see Figs. 3 and 5,) of which one, *H*, is mounted 80 on the frame *k* and the other, *I*, is mounted on the support *r*. This latter, *I*, has in it a curved slot, (see Fig. 5,) in which moves a pin, *K'*, serving as a guide to the key during its displacement. The fingers *L* of the key have at 85 their front ends inclined beaks, upon which the points of the cylinder act to raise them as the cylinder rotates. The said fingers are pivoted to forked flanges *V*, secured to a fixed longitudinal beam, *M*. This latter carries on its 90 upper part the spring *Q* and on its lower part a comb, *N*, and at the back of it are arranged the chucks *O* and the push-pins *P*, which are in number equal to the fingers *L*. Each push-pin *P* is connected with a spring, *Q*, intended 95 to constantly press back the beaks of the fingers *L* into contact with the cylinder or the points thereof, and to press the push-pin upward. The upper part of each push-pin is terminated by a buffer or soft button, *R*, for striking one of the jacks of the piano-forte action *T* every time a point on the cylinder passes by the beak of a finger. The spring *Q*, which has been strained by the action of the cylinder-tooth on the finger, then reacting to 100 throw up the push-pin, and thereby throw up the jack against the hammer-butt. 105

The action may be of ordinary construction, or similar to that used with a manual key-board in ordinary piano-fortes, as shown in Fig. 1.

It may be remarked that the action of the push-pins *P* does not in any way affect the operation of the ordinary keys of the piano, either while they are in operative position 115 shown in Fig. 6, or in the inoperative position shown in Fig. 7. The action of the piano is completely independent, and may be played either on the ordinary key-board or by the special keys operated by the cylinder. 120

What I claim as my invention, and desire to secure by Letters Patent, is—

The combination, with the cylinder, of the gudgeon *q*, provided with circumferential grooves *s* and a screw-thread, the nut *t*, the fixed pin *u*, the roller *t'*, arranged on another fixed pin, and the spring *v* and the knife-edged slide *C* *D*, all substantially as herein described.

JEAN LACAPE.
